UNITED STATES PATENT OFFICE.

FREDERICK MAX PORITZ, OF NEW YORK, N. Y., ASSIGNOR TO ARTISTIC BRASS & BRONZE WORKS, INC., OF NEW YORK, N. Y., A CORPORATION OF NEW YORK.

DESIGN FOR A COLUMN FOR ELECTRIC-LIGHT FIXTURES OR SIMILAR ARTICLES.

Application filed February 23, 1927. Serial No. 20,865. Term of patent 3½ years.

To all whom it may concern:

Be it known that I, FREDERICK MAX PORITZ, a German citizen, and a resident of the borough of Manhattan, city, county, and State of New York, have invented a new, original, and ornamental Design for Column for Electric-Light Fixtures or Similar Articles, of which the following is a specification, reference being had to the accompanying drawing, forming a part thereof.

Fig. 1 of said drawing is an elevational view of a column of my new design show-

ing only a portion of the ornamentation of the column in detail, it being understood that the balance of the unornamented portion is a mere repetition of that portion more fully shown.

Fig. 2 is a plan view of a column showing my new design.

I claim:

The ornamental design for a column for electric light fixtures or similar articles, as shown and described.

FREDERICK MAX PORITZ.
